United States Patent Office

Des. 179,344
Patented Dec. 4, 1956

179,344

COVER FOR A BOX

Benjamin Greenstein, Bronx, and Carl Molk,
New York, N. Y.

Application September 19, 1955, Serial No. 37,988

Term of patent 7 years

(Cl. D58—11)

FIG. 1.

FIG. 2.

FIG. 3.

FIG. 4.

Fig. 1 is a top plan view of a cover for a box, showing our new design;

Fig. 2 is a front elevational view thereof;

Fig. 3 is a side elevational view thereof; and

Fig. 4 is a radial cross-sectional view thereof.

The rear view and the opposite side view of the cover for the box are the same as the front and side elevational views, respectively, as shown.

We claim:

The ornamental design for a cover for a box, as shown and described.
